CLAIM

We claim the ornamental design for ocular aerosol goggles, as shown and described in the following Figures.

DESCRIPTION

FIG. 1 is a perspective view of the goggles.

FIG. 2 is a front view of the goggles.

FIG. 3 is a back view of the goggles.

FIG. 4 is a left side view of the goggles.

FIG. 5 is a right side of the goggles.

FIG. 6 is a top view of the goggles; and,

FIG. 7 is a bottom view of the goggles.
